UNITED STATES PATENT OFFICE.

JOSEPH FARRIS, OF SPRINGFIELD, ILLINOIS.

FURNACE-JOINT.

1,342,258.

Specification of Letters Patent. Patented June 1, 1920.

Application filed August 28, 1918. Serial No. 251,818.

To all whom it may concern:

Be it known that I, JOSEPH FARRIS, a citizen of the United States, residing at Springfield, in the county of Sangamon and State of Illinois, have invented certain new and useful Improvements in Furnace-Joints, of which the following is a specification.

This invention relates generally to furnace 10 or stove structures, and aims primarily to provide improvements in means for securing the dome and fire pot together, so that the said dome and fire pot are in effect a unitary structure.

15 A further object of the invention is to provide a furnace structure of such character that its dome and fire pot may be readily applied to or removed from each other without the instrumentality of such 20 devices as have heretofore been employed, and which is of such character that the said dome and fire pot are firmly locked together at their points of connection.

With these objects in view, together with 25 others which will appear as the description proceeds, the invention resides in the novel formation, combination and arrangement of parts, all as will be described more fully hereinafter, illustrated in the drawings, and 30 particularly pointed out in the claim.

In the drawings:—

Figure 1 is a vertical sectional view taken 35 through the dome and fire pot, constructed in accordance with the invention and illustrating the same as they will appear when locked together,

Fig. 2 is an inverted plan view of the dome,

Fig. 3 is a fragmentary side elevation 40 showing one of the locking devices,

Fig. 4 is a perspective view of one of the locking hooks,

Fig. 5 is a perspective view of one of the locking wedges, and

Fig. 6 is a detail fragmentary sectional 45 view illustrating locking means of slightly modified form.

The firepot of the interior furnace structure is indicated generally at 7, and comprises a tubular member having an annular flange 8 at its upper end. This flange projects outwardly from the fire pot 7 and has an upturned flange or rib 9 at its outer edge. The part, indicated at 10, is the dome, and 55 is closed at its upper end as shown. This

dome is provided with the usual flue opening 11. The lower edge of the dome rests upon the outwardly projecting flange 8 of the fire pot 7.

Arranged in spaced relation around the 60 dome 10 and upon the exterior surface thereof near its lower end, are a plurality of outwardly projecting lugs 12, each of which has its outer end turned upwardly in a hook as at 13. These lugs are preferably 65 formed integral with the dome, and receive the upper extremities of retaining hooks 14. The retaining hooks have openings 15 at their upper ends to engage over the hooks 13, and are provided with inturned lower 70 ends or bills 16 designed to pass beneath the annular flange 8 of the section 7. Wedges 17 formed of cast iron or other suitable metal are driven between the inturned bills 16 of the hooks 14 and the lower surface of 75 the flange 8, and it is obvious that the driving of these wedges in this manner causes the upper and lower ends respectively of the fire pot and dome to be forcibly brought together and firmly so held. When 80 thus properly secured, the dome and fire pot are held together as a unit, and when it is desired to separate the dome and fire pot, it is but necessary to withdraw the wedges and to remove the hooks 14. 85

In Fig. 6 of the drawings, there is illustrated a slightly modified form of the invention, wherein the wedges heretofore described are omitted. In this modified form of the invention, the clamping action between the hooks 14 and the flange 8 is obtained by passing screws 18 upwardly through the inturned bills 16 of the hooks. These screws engage with the under surface 90 of the flange 8 and firmly bind the fire pot 95 and dome together.

From the foregoing it is obvious that I have provided a means of extremely simple construction for securing the dome and fire pot together, and yet the parts may be 100 readily separated when required.

The foregoing description and the drawings have reference to what may be considered the preferred or approved form of my invention. It is to be understood that I 105 may make such changes in construction and arrangement and combination of parts, materials, dimensions, etc., as may prove expedient and fall within the scope of the appended claim.

Having thus fully described the invention, what I claim as new and desire to secure by Letters Patent is:—

A furnace joint in combination with a fire pot and a dome, said fire pot having an annular flange adjacent its upper portion and said dome resting upon said flange, said dome having upwardly bent hooks, retaining hooks having a comparatively 10 square and flat upper portion provided with comparatively square openings, the portions above said openings adapted to completely fill the space between said upwardly bent hooks and said dome thereby preventing outward movement of the lower portions of 15 said retaining hooks, said retaining hooks being curved outwardly toward their lower

portion and then being bent to form inwardly extending horizontal bills, whereby said retaining hooks may pass around the 20 lower portion of the flange of the fire pot, to allow said bills to extend around said flange, and means carried by said bills to jam against the under surface of said flange, thus urging said bills downwardly from said flange, whereby said retaining hooks will 25 firmly hold said dome upon said fire pot.

In testimony whereof I affix my signature in presence of two witnesses.

JOSEPH FARRIS.
